DESIGN FOR A CANDLESTICK HOLDER

Rinaldo Minervini, Detroit, Mich.

Application March 28, 1946, Serial No. 128,023

Term of patent 3½ years

(Cl. D48—2)

To all whom it may concern:

Be it known that I, Rinaldo Minervini, a citizen of the United States, residing at Detroit, in the county of Wayne and State of Michigan, have invented a new, original, and ornamental Design for a Candlestick Holder, for which the following is a specification, reference being had to the accompanying drawing, forming part thereof, in which:

Fig. 1 is a perspective view of the candlestick holder showing my new design; and

Fig. 2 is a top plan view thereof.

I claim:

The ornamental design for a candlestick holder, substantially as shown.

RINALDO MINERVINI.
